Primary Examiner — Austin Murphy(74) *Attorney, Agent, or Firm* — Sheppard Mullin Richter & Hampton(57) **CLAIM**

We claim the ornamental design for a head-mounted display with magnetic battery temples, as shown and described.

DESCRIPTION

FIG. 1 is a perspective view of a head-mounted display with magnetic battery temples embodying the new design. FIG. 2 is a front view of the head-mounted display with magnetic battery temples embodying the new design. FIG. 3 is a rear view of the head-mounted display with magnetic battery temples embodying the new design. FIG. 4 is a first side view of the head-mounted display with magnetic battery temples embodying the new design. FIG. 5 is a second side view of the head-mounted display with magnetic battery temples embodying the new design. FIG. 6 is a top view of the head-mounted display with magnetic battery temples embodying the new design; and, FIG. 7 is a bottom view of the head-mounted display with magnetic battery temples embodying the new design. The broken lines illustrate portions of the head-mounted display with magnetic battery temples that form no part of the claimed design.
